UNITED STATES PATENT OFFICE.

CHRISTIAN DORN, OF PHILADELPHIA, PENNSYLVANIA, ASSIGNOR OF ONE-HALF TO
CHARLES W. KARST, OF PHILADELPHIA, PENNSYLVANIA.

BOTTLE-STOPPER.

1,177,399.

Specification of Letters Patent. Patented Mar. 28, 1916.

Application filed June 25, 1914. Serial No. 847,209.

To all whom it may concern:

Be it known that I, CHRISTIAN DORN, a citizen of the United States, residing in Philadelphia, Pennsylvania, have invented 5 certain Improvements in Bottle-Stoppers, of which the following is a specification.

The main object of my invention is to so construct a device for preventing the refilling of bottles as to insure a free flow from 10 the bottle in pouring out its original contents, another object being to so construct the device that the same cannot be removed from the neck of the bottle without such mutilation as will show that it has been tampered with. These objects I attain in the 15 manner hereinafter set forth, reference being had to the accompanying drawings, in which—

Figure 1 is a vertical sectional view showing in upright position the neck portion of 20 a bottle provided with a device in accordance with my invention to prevent refilling of the same after its original contents have been dispensed; Fig. 2 is a similar view 25 showing the same in the tilted or pouring position; Fig. 3 is a side elevation of the stopper removed from the neck of the bottle; Fig. 4 is a horizontal section on the line *a—a*, Fig. 1, and Fig. 5 is a horizontal section on the line *b—b*, Fig. 1.

In the drawing, 1 represents the neck portion of a bottle to which my improved stopper is intended to be applied, said neck portion having formed therein, some distance 30 below the mouth, an internal annular recess 35 for the reception of a pair of split sealing and locking rings 2 and 3 of cork or other available material, which also engage with the tubular body 4 of the stopper and prevent 40 the removal of the same from the bottle neck, said tubular body 4 having at the lower end a sealing ring 5 of cork or equivalent material which will prevent the passage of liquid from the bottle around the body 4 45 and will cause all liquid escaping from the bottle to pass through a central aperture 6 which, when the bottle is in the upright or upwardly inclined position, is closed by means of a valve 7 shown in the present instance as a spherical body adapted to an 50 appropriately shaped seat in the body 4 at the top of the aperture 6, as shown in Fig. 1.

In the side walls of the body 4 are formed two sets of openings 8 and 9 one above the

other, and at the top of said body 4 is 55 formed an internal screw thread to which is adapted a corresponding external thread formed upon a cap structure 10 which, when screwed into the body 4, confines the rings 2 and 3 to their seat on said body, as shown 60 in Fig. 1.

The cap 10 contains a chamber 11 which is closed at the bottom but communicates through openings 12 with the upper portion of the chamber within the tubular body 4, 65 and from said cap member depend a series of elastic fingers 13 which constitute a cage for receiving and retaining the valve 7 when the latter moves away from its seat on the tipping or tilting of the bottle, as shown in 70 Fig. 2.

The lower ends of the fingers 13 have projecting and tapering studs 14, as shown in Fig. 5, these studs projecting into the openings 8 in the walls of the body structure of the stopper and thus serving as ratchet teeth to prevent the unscrewing of the cap structure 10 when the same has been 75 screwed into the body structure to its proper position in respect thereto, the inclined sides 80 of the studs 14, by contact with the forward edges of the openings 8, causing the fingers 13 to be pressed inwardly during the forward movement of the cap but the abrupt rear ends of said studs 14 contacting with 85 the rear walls of the openings 8 and preventing backward movement of the cap if any attempt is made to unscrew the same.

The split rings 2 and 3 are free to expand or contract to a limited extent, and in applying the stopper to the neck of the bottle in the first instance the body 4 (to which the cork ring 5 has previously been applied) is inserted into the neck until it assumes its proper position therein, the rings 2 and 3 90 being then contracted until they can pass through the neck of the bottle above the annular recess therein, said rings expanding 95 when they come into line with the recess so as to engage both the neck of the bottle and the body member 4 of the stopper and prevent the removal of the latter from said bottle neck. The valve 7 is then applied to its seat in the lower portion of the body and the cap member 10 then screwed into position, as shown in Fig. 1, so as to confine the 100 rings 2 and 3 to the body member and cause the studs 14 to engage with the openings 8 105

so as to prevent subsequent removal of the cap.

When the bottle is held in the tipped or pouring position shown in Fig. 2 the liquid can readily escape from the bottle through the passage 6, hence around the lower portion of the cap, and through the lower openings 8, 9 and 12, and the passage between the underside of the stopper body 4 and the underside of the bottle neck, into the chamber 11, from which it flows into the neck of the bottle beyond the stopper and thence from the mouth of the bottle. Air entering the bottle through the upper openings 12, 9 and 8 and the aperture 6 takes the place of the liquid which is discharged, so that a continuous stream of considerable volume can be poured from the bottle during the entire time that the same is held in tipped or pouring position.

The holding of the valve 7 away from its seat by means of wires or other flexible instruments introduced through the chamber 11 of the stopper is prevented by reason of the fact that the openings 12 of the cap are out of line with the openings 9 in the body of the stopper and the fingers 13 of the cap are in line with the openings 12 and in front of the openings 8 in the stopper body.

While I have shown split rings co-operating with an internal annular recess in the bottle neck as a means of preventing withdrawal of the stopper from said neck, other means may, if desired, be used for the purpose of locking the stopper in the neck of the bottle, and while I prevent unscrewing of the cap member of the stopper by causing the tapering studs at the lower ends of the elastic fingers 13 to engage with the openings 8 in the stopper body, an otherwise located ratchet device may, if desired, be employed for this purpose.

Copies of this patent may be obtained for five cents each, by addressing the "Commissioner of Patents, Washington, D. C."

I claim:—

1. The combination of the bottle neck having an internal annular recess therein, a stopper; a sealing ring engaging said recess in the bottle neck and seated upon the body member of the stopper, and a cap member for said stopper separate from the body member but locked in position therein and bearing upon said sealing ring so as to retain it in position upon the body member.

2. The combination of the bottle neck having an internal annular recess therein, a stopper, a sealing ring engaging said recess and seated upon the body member of the stopper, a cap member separate from the body member of the stopper but screwed into said body member and serving to retain the sealing ring in position thereon; and a ratchet device for preventing the unscrewing of said cap member.

3. The combination of the bottle neck having an internal annular recess therein, a stopper having a body member with an inlet passage and side openings, a valve for closing the inlet passage, a sealing ring seated upon said body member of the stopper and engaging the recess in the bottle neck, and a cap member separate from the body member of the stopper but screwed into the same, said cap member having a discharge passage therein and openings leading to said discharge passage, and a valve-receiving cage consisting of spring fingers having tapered studs for engaging with the side openings in the body member of the stopper to prevent backward movement of said cap.

In testimony whereof, I have signed my name to this specification, in the presence of two subscribing witnesses.

CHRISTIAN DORN.
